UNITED STATES PATENT OFFICE

2,536,319

OVERLOAD PROTECTIVE DEVICE

Howard N. Slack, Los Angeles, Calif.

Application September 14, 1946, Serial No. 697,035

4 Claims. (Cl. 192—150)

1

My invention in its broadest aspect pertains to a torque responsive overload protection device. I have developed this invention in connection with, and have applied it to, a frozen food mixer adaptable to domestic mechanical refrigeration cabinets. Whereas, the specifications hereinafter to follow will describe my invention in connection with an ice cream freezer adapted to domestic refrigeration cabinets, it will be understood that the overload protection device above referred to may be applicable to a wide variety of uses wherein it is desired to protect any power mechanism against a torque overload.

In the manufacture of ice cream, it is essential to continuously agitate the mixture while it is being congealed in order to prevent either the separation of any of the constituent materials or the formation and growth of ice crystals. This purpose is accomplished by the rotating of a plurality of paddles in the container into which the constituent mixture has been placed for freezing. The rotation of the paddles may be accomplished by, among others, the use of an electric motor. The principal weakness of such a system lies in the fact that as the constituent mixture begins to congeal, its viscosity becomes greater thereby increasing the torque loading of the electric motor. This will reach a point where it is dangerous to the safety of the electric motor.

It is an object of my invention to provide a device for coupling the drive shaft of the electric motor to the shaft of the paddle assembly, which will be responsive to a torque loading and disconnect the electric circuit when the torque load reaches a predetermined maximum.

Numerous overload protection devices are known to the art. Most of the heretofore known overload protection devices are complicated in their structure and expensive to manufacture. It is a further object of my invention to provide such a torque responsive overload protection which will be simple and inexpensive to manufacture and easily assembled into the domestic refrigeration cabinet.

A further specific object of my invention is to provide a container for freezing various types of food, such as ice cream, which is not permanently attached to the refrigeration cabinet thereby economizing in the use of space within the cabinet, and which is, at the same time, easily operable and easy to assemble and remove. Further objects and advantages of my invention will become apparent from the drawings and specifications relative thereto.

2

In the drawings:

Figure 1 is a side elevation, partially in section, of an ice cream freezer embodying the principles of my invention.

Figure 2 is an end elevation taken from the right-hand side of Figure 1.

Figure 3 is a partial plan view of the right-hand end of Figure 1.

Figure 4 is a sectional view taken on line 4—4 of Figure 1.

Figure 5 is a detailed plan view, partially in section, of the torque responsive protective device.

Figure 6 is a detailed section view of the mounting or the drive shaft through the cabinet wall.

Figure 7 is an enlarged detailed view of the coupling device between the drive shaft and the ice cream freezer.

The essential features of my invention in the preferred embodiment include a freezing container 10 disposed within an evaporator coil 11, an electric motor 12, and a torque responsive overload protection designated generally 13, mounted in an undercut portion of a refrigerator cabinet 14.

25 The freezing container 10 is generally of a standard construction and comprises a cylindrical container 20 closed at one end by a bottom 21 as an integral part thereof, and closed at the other end by a removable cover 22. The removable cover 22 is formed with a depending annular flange 23 adapted to frictionally engage the cylindrical wall 20. Sealing means are provided, such as the rubber gasket 24 to render the joint between the cover 22 and the cylindrical wall 20 liquid tight. The cover 22 is formed also with an axially disposed boss 25 having a bore 26 disposed therethrough into which a bearing surface 27 is secured by any suitable means, such as a friction fit. The bottom 21 is formed with a centrally disposed boss 28 having a centrally disposed bore 29 therein.

Any suitable means may be provided for agitating the constituent mixture as it is being congealed. I prefer and have illustrated an agitating device which comprises a plurality of paddles 30 attached to a plurality of radially extending arms 31 and disposed adjacent and parallel to the cylindrical wall 20. The radially extending arms 31 are securely attached to a centrally disposed pivot point 32 on one end, and a centrally disposed driving shaft 33 on the other end formed at its free end with any suitable non-rotatable couple, such as the square end 33a. The pivot point 32 is adapted to pivot or rotate in the bore 29. The shaft 32 is rotatably dis-

40

55

posed in the bore 26. Means for driving or rotating the paddle assembly comprise any standard electric motor, such as motor 12. The motor 12 is mounted externally on the refrigeration cabinet 14 by means of bolts 34.

Means for coupling a drive shaft 12a of motor 12 to the driven shaft 33 of the paddle assembly include the overload protective device 13. The overload protective device 13 comprises a cup-shaped member 40 having a centrally disposed boss 41 formed with a bore 42 therethrough, a driving member or radial arm 43 having a centrally disposed boss 44 formed with a centrally disposed bore 45 therethrough. It will be understood that a spider or any other suitable bracket will be considered as an equivalent of the cup-shaped member 40. A plurality of axially directed pivot posts 46 are securely mounted in the cup 40 by any suitable means, such as for example, projection welding. Pivot posts 46 are formed with slots 47 in the upper end thereof. A plurality of camming members 48 are pivotally disposed in the slots 47. The cup 40 is formed with a plurality of inwardly extending loops 50. The camming member 48 is urged into engagement with the radial arm 43 by means of springs 51 or other suitable biasing means connected in tension between the camming member 48 and the loops 50. The cup 40 is also formed with a plurality of slots 52 in the base of said cup adapted so that upon rotation of the camming member 48, the end thereof will pass through the slot 52. A plate 60 is pivotally mounted by being secured to pivot rod 61, and if formed with a projection 62 extending at right angles to the principal plane of plate 60 and a centrally disposed elliptical bore 63. The plate 60 is positioned with respect to the cup 40 so that upon rotation of the camming members 48, the camming members 48 will press against the plate 60 and cause it to rotate in a counter-clockwise direction taken in the view of Figure 1.

The means for connecting the cup 40 with the paddle assembly comprise a shaft 70 disposed in the bore 42 of the boss 41, and is detachably connected to the shaft 33 by means of a spline fitting which comprises members 71 and 72. The spline member 71 is formed with slidable couple 71a adapted to cooperate with the square end 33a so that it is slidably and non-rotatably mounted on the end of shaft 33 and is urged outwardly from shaft 33 by means of a spring 73. The spline member 72 is securely mounted on the shaft 70 by any suitable means, such as a pin or a left-hand thread.

The shaft 70 is rotatably mounted through the wall of the cabinet 14 by means of an assembly which comprises a substantially tubular-shaped member 80, which is internally threaded at the inner end 81 and externally threaded at the outer end 82. A lock nut 83 secures the outer end 82, and a flanged member 84 secures the inner end of the tubular member 80 in the wall 14 of the cabinet. The flanged member 84 is formed with a centrally disposed bore 85 adapted to receive a spring 86, which urges a sealing ring 87 against a washer 88 and a smaller bore 89 adapted to receive a bearing 90. The shaft 70 is formed with a shoulder 91 to prevent the shaft 70 from being urged through the bore 89 by the spring 86.

The freezing container is removably and non-rotatably mounted in the evaporator coil 11 by means of the bracket 100 which is secured to the base 21 of the container 10 and is prevented from rotating by means of lugs 101. The bracket

100 is formed in a substantially U-shape, having substantially S-shaped arms 102 adapted to engage the sides of the evaporator unit 11.

When it is desired to insert the freezing unit 10 into the evaporator coil 11 and into operative connection with the drive shaft 70, the unit is pushed into the evaporator coil with the spline member 71 approximately aligned with the spline member 72. In the event that the splines do not match, the freezing unit 10 may be pushed inwardly of the coil 11 until the bracket 100 securely engages the sides of the evaporator coil 11. The spline member 71 will be urged inwardly on shaft 33. As soon as the motor 12 commences to drive the shaft 70 and rotate the spline member 72, the splines of the spline members 71 and 72 will become matched, and the spline member 72 will be urged outwardly on shaft 33 by means of the spring 73.

Upon removal of the freezing unit 10 from the evaporator coil 11, the spline member 72 may be covered by a cap 110 adapted to fit over the flanged member 84 in frictional engagement.

The operation of my overload protective device 13 is as follows: The motor 12 being operatively connected to the radial arm 43 rotates the arm 43 in a counter-clockwise direction (Figure 4). The camming members 48 are urged against the leading edge of the radial arms 43 by means of the springs 51, thereby causing the cup 40 also to rotate in a counter-clockwise direction.

When the constituent mixture in the freezing container 10 congeals to a predetermined viscosity, the torque required to rotate the paddles 30 becomes greater than the strength of the springs 51. The springs 51 therefore yield and the camming members 48 are caused to rotate outwardly from the center of the cup 40 until they engage the surface of the plate 60. The plate 60 is then caused to rotate in a counter-clockwise direction (Figure 1), thereby raising the projecting arm 62 into contact with the normally closed microswitch 64. When the projecting arm 62 has been displaced at predetermined distance, the microswitch 64 opens, thereby breaking the circuit which is energizing the motor 12, and turning off the assembly.

It will be obvious that the motor shaft 12a and the freezer coupling shaft 70 are axially aligned, and that they constitute in effect a single shaft in two separated sections. In the claims the latter phrase is employed; namely, a shaft in two separated but axially aligned sections, as a matter of convenience, and is intended to include the obvious equivalent of two individual axially aligned shafts.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

Having described my invention, what I claim as new and desire to secure by Letters Patent is:

1. A torque coupling and protective device for an electric motor comprising a shaft in two separated but axially aligned sections, a pair of diametrically opposed radial arms secured to one of said sections for rotation therewith, a pair of camming members associated with the other of said sections for rotation therewith and adapted to engage one edge of said radial arm, 70 resilient means adapted to bias said camming

members into contact with said arms but to yield to permit pivotal movement of said camming members upon the application of an excessive torque, a lever positioned adjacent said camming members for contact thereby upon application of an excessive torque through said torque coupling and adapted upon said torque application to actuate a switch for controlling said electric motor.

2. A torque coupling and protective device for an electric motor comprising a shaft in two separated but axially aligned sections, a radial arm secured to one of said sections for rotation therewith, a camming member associated with the second of said sections for rotation therewith and adapted to engage one edge of said radial arm to cause rotation of said other section, a spring member associated with said second shaft section for rotation therewith and adapted to bias said camming member into contact with said arm but to yield to permit pivotal movement of said camming member upon the application of an excessive torque, a pivotal switch actuating plate positioned adjacent said camming member for contact therewith upon application of an excessive torque through said torque coupling and adapted upon said torque application to actuate a switch for controlling said electric motor.

3. In combination with an electric motor and a control switch therefor, a torque transmitting and overload protective device comprising a shaft in two sections in axial alignment, a radial arm associated with one of said sections for rotation therewith, a cup associated with the other of said sections for rotation therewith, said cup having a base and side wall, a pair of camming fingers pivotally secured to said cup, each of said fingers having an edge adapted to abut against the leading edge of said radial arm, resilient means adapted to bias said fingers into abutment with said radial arm, and to yield upon the application of an excessive torque to cause a pivoting motion of said finger, a switch actuating plate pivotally mounted adjacent said cup so that said switch plate will be contacted and pivoted

by a pivoting of said cam finger, said switch actuating plate being adapted to actuate said control switch upon being pivoted by said camming finger.

- 5 4. In combination with an electric motor and a control switch therefor, a torque transmitting and overload protective device comprising a shaft in two sections and axially aligned, and resilient means for coupling said sections together for torque transmission, said means comprising a radial arm associated with one of said sections for rotation therewith, a cup secured to the other of said sections for rotation therewith and adapted to enclose said radial arm, said cup having a base and side wall, a pair of camming fingers pivotally secured to said cup, each of said fingers having an edge adapted to abut against said radial arm, resilient means adapted to bias said fingers into abutment with said radial arm, and to yield upon the application of an excessive torque to cause a pivoting motion of said fingers, said means comprising a tension spring secured between each of said fingers and the wall of said cup on the opposite side of said arm, a switch actuating plate pivotally mounted adjacent said cup so that said switch plate will be contacted and pivoted by a pivoting of said cam fingers, said switch actuating plate being adapted to actuate said control switch upon being pivoted by said camming fingers.
